Original design application Dec. 13, 1965, Ser. No. 517,
now Patent No. 205,931, dated Oct. 11, 1966. Divided
and this application June 16, 1966, Ser. No. 2,708

Term of patent 14 years

(Cl. D13—1)

FIG. 1

FIG. 2

FIG. 1 is a front elevational view of a restaurant building facade showing my new design, and

FIG. 2 is a side view of the structure of FIG. 1.

The ornamental design of my restaurant building facade is generally characterized by a wheeled circus-wagon facade simulating barred cages with convoluted ornamental borders.

This application is a division of application Serial No. D.517, filed December 13, 1965, for Restaurant Building, in the name of Edwin H. Eichler now Patent No. D.205,931.

I claim:

The ornamental design for a restaurant building facade, substantially as shown and described.
